UNITED STATES PATENT OFFICE.

JOHN J. CULLINAN, OF CHICAGO, ILLINOIS.

PROCESS OF IMPREGNATING ARTICLES WITH GUT.

Application filed April 17, 1922. Serial No. 554,325.

To all whom it may concern:

Be it known that I, JOHN J. CULLINAN, a citizen of the United States, and a resident of Chicago, in the county of Cook and State of Illinois, have invented certain new and useful Improvements in Processes of Impregnating Articles with Gut.

This invention relates to a method or process of impregnating wooden or metallic articles with gut. The articles contemplated as subject to the process may be generally classified as implements or parts of implements which are made use of in striking blows, or imparting movement to other articles or objects by a swinging motion of the head or striking portion of the implement against the moving or stationary object, such as a ball.

The foregoing description suggests implements used in playing at the various forms of sport, and it is contemplated that the invention, may be utilized in improving the structure and quality of the many implements of sport and play, such as golf clubs, tennis rackets, baseball bats, croquet mallets, billiard cues, and even the more commercial or industrial implements, as jewelers' hammers and other tools of like character.

The object of the invention is to provide a new and novel construction for articles or implements of the character described utilizing what is commonly called "cat-gut," or simply "gut", a tough and silent animal tissue procured from the intestinal tract of sheep, and by a process or treatment reduced to its commercial form in smooth strands or threads of uniformly circular section. As a material, its qualities are well known. Its high tensile strength, resiliency, elasticity, produces a combination of qualities which is not possessed by any other substance for surgical thread, strings for musical instruments, for tennis rackets and like purposes.

The use of this substance may also be extended as a medium of reinforcing and strengthening the material of which implements are made, and also as a binding or connecting material, where metallic fastening members would otherwise be used.

In the application of the gut to various forms of articles and implements, the method or process involved is generally the same, to wit: the impregnation of the article with one or more strands of gut, ordi-

narily extending at right angles to the contact face, and in line with the direction of the force delivered against the object or ball struck. The strand or strands furthermore, extend a considerable distance into the material impregnated, and more often, completely through it, one feature of the process being the method of anchoring the ends of the strand in place so that it becomes an integral part of the material.

In the drawings are illustrated several applications of the impregnating process, each embodying the same principle, but varying somewhat in the results attained.

Figure 1 is a fragmentary view of a single strand passing through any article, showing the general principle of the process.

Figure 2 is a view in longitudinal section of the neck portion of a tennis racket, showing the use of gut as a reinforcing and fastening material.

Figure 3 is a fragmentary view of a mallet head, showing the strands.

Considering the process in its broadest aspect, it consists in boring or drilling a hole through the article to be treated, the line or direction of the bore being cross-wise of the grain, or transverse to the place of cleavage between the fibers of the wood, or parallel to the direction of the blow delivered, depending on the particular implement. The hole or bore is of a size to permit a strand of gut, to be drawn or forced through the same with a snug fit. Before the strand is inserted, it is preferably dipped in hot glue, the insertion being completed without delay and before the moisture and heat has an opportunity of affecting the gut. Having inserted the strand within the bore, it will immediately swell, due to the application of the glue, and become firmly lodged in place, the glue acting as a cement or adhesive. The ends of the strand will ordinarily project from the surface of the article, and these ends are then treated so that they are firmly anchored, this being especially desirable in case the strand is to be subjected to tension.

In the first place, the ends are trimmed close to the surface, and then a hot iron or flame is momentarily applied to the exposed ends, thus searing or burning the substance, and causing it to swell for an appreciable distance inwardly from the ends. When the substances have cooled and hardened, a perfect enlargement or head not unlike a rivet

head is formed. In fact, these enlargements or heads act in the same manner as a rivet head, preventing the slightest endwise movement of the strand. The gut having been 5 inserted with a previous application of glue and the subsequent searing of the ends, produce a permanent and integral impregnation of the gut substance, as impervious to exterior condition, and as lasting as the 10 impregnated material itself.

The advantages are many fold. In the first place, the gut is lighter than the material in most cases used, so that greater lightness in weight may be obtained with- 15 out a material sacrifice in density; secondly, the gut is more resilient than wood, so that the resiliency of the implement or part impregnated is increased; (a golf club head is a good example of the desirability of 20 added resiliency); and thirdly, the tenacity of the gut is greater than the tenacity of the fibres of the wood, to the end that the wood is reinforced and strengthened against cracking and splitting.

25 Considering now the various applications of the process, Figure 1 illustrates the manner in which a body of wood A is impregnated with a single strand of gut B, in accordance with the method hereinbefore 30 set forth. The strand passes through from face to face, and crosswise of the grain, and the ends thereof, treated to provide the heads of enlargements b, b. While a single strand is shown, it is understood that a 35 plurality of such strands would be used, so that the entire contact area or face and portion immediately behind would be thoroughly impregnated with gut. In carrying out the process relatively large strands of 40 gut, of say, one eighth ($\frac{1}{8}$) inch diameter is preferred. The manifest results of such treatment, would be increased resiliency and strength, and decreased weight, although this last effect is not so material, 45 except as a means of securing proper balance or distribution of the weight.

A further application of the process is in the construction of tennis rackets (Figure 50 2). The head of a tennis racket consists of an annular frame C, formed from a single 55 length of wood, bent to shape, and the ends c c brought together to form the neck, and the central core of the racket handle. A wedge shape piece D is inserted between the 60 ends of the head forming member, and these parts together form the throat of the racket. Ordinarily these parts are secured together by a metal pin or rivet extending transversely through the parts.

65 As clearly shown in Figure 2, a length of gut E, of say one eighth inch diameter, passes completely around the frame of the racket. The gut terminates in free end portions e e, which are threaded through bores, 70 f f, alternately inclined in opposite direc-

tions to the axis of the handle, in zig-zag form, the bores for each end being offset in parallel planes, an oblique bore extending substantially at right angles to a corresponding bore in the other parallel plane. 70 The method of threading the gut through the bores is the same as already described, the extremities being enclosed by searing the exposed end surfaces in the suggested manner. This application of gut suggests 75 the locking of the parts together, throughout the length of the throat, but differing therefrom, in that the gut is permanently embedded or impregnated into the wood, and its ends anchored against removal. By 80 this process, the use of metal is entirely eliminated as a fastening means, the binding effect is distributed throughout the entire extent of the throat or neck, and the weight of the racket is not disturbed appreciably although whatever change is produced is for decreased weight. Furthermore, greater resiliency is obtained in the 85 racket frame.

A third application of the method is 90 illustrated in connection with a cylindric body (Figure 3) which may represent the head G of a roque mallet or the like. Here again the strands of gut H are inserted completely through the head, although 95 axially thereof, that is, at right angles to the striking faces of the head. Inasmuch as playing mallets are not subjected to hard usage, the strengthening of the same against breakage is not so essential as imparting to the head the quality of resiliency. Hence the strands are located with respect to the direction of the blow struck by the mallet head rather than with any relation 100 to the grain of the wood.

105 Similar applications of impregnating gut would be resorted to in treating polo sticks and billiard cues, regard being had in each instance to the manner in which the article is to be used. For example in a billiard cue, a single strand of relatively large gut would be extended axially from end to end. The result would be a central core of gut, 110 imparting resiliency in a lengthwise direction, increased lightness and improved balance, and elimination of a tendency to warp out of shape. Manifestly it would be impossible to consider every use to which this process may be employed and the particular 115 advantages that would be derived in each case. Therefore it is to be understood that it is not the intention to limit the invention to the use disclosed herein, but includes any 120 and all applications coming within the scope of the appended claims.

125 What I claim as my invention is:

1. A solid body having a strand of gut 130 passing therethrough and secured against displacement in the body, one end at least being secured by a heat expanded enlarge-

ment substantially flush with the surface of the body.

2. A solid body for concussive use having a strand of gut passing through and tightly fitting with a bore passing through said body, said strand being held against movement in said body by heat expanded enlargements at the ends of said gut substantially flush with the surface of the body.

10 3. A solid body laced with a strand of gut passing therethrough and secured against movement in the body by a heat expanded enlargement at one end at least of the strand, substantially flush with the 15 surface of the body.

4. An implement for concussive use comprising a solid body portion laced with a strand of gut passing through said body and secured against movement in said body by 20 the enlargement of the strand by heat expansion.

5. An implement for concussive use, comprising a solid body portion laced with a strand of gut passing through holes bored in 25 said body and held against movement in said body by the expansion of said strand by heat, and heat expanded enlargements at the ends thereof substantially flush with the surface of said body.

30 6. The process of lacing a solid body with gut consisting in perforating the body, providing a gut strand, coating said strand with a softening adhesive and, before the adhesive has softened the gut, passing said 35 strand through the perforation, then permit-

ting it to soften and assimilate itself to the walls of the perforation and finally securing the ends against drawing through the perforation by enlarging them by searing.

7. The process of lacing a solid body with 40 gut consisting of perforating the body, inserting a strand of gut through said bore, said gut being previously treated to effect the permanent retention of the gut, and finally 45 enlarging the ends of the strand by searing.

8. The process of lacing a solid body with gut consisting of perforating the body with a plurality of holes, coating strands of gut with an expanding agent, inserting the 50 strands within said holes before the expansion has been effected, and finally searing the ends of the strands at the surface of the body.

9. The process of lacing a solid body with 55 gut consisting of perforating the body parallel with the direction of concussion providing a gut strand, coating said strand with a softening adhesive and before said adhesive has softened the gut passing said 60 strand through the perforation, then allowing the gut to soften and assimilate itself to the walls of the perforation and finally securing the ends against drawing through 65 the perforations by enlarging the same by searing.

In witness whereof, I hereunto subscribe my name this 13th day of April, A. D., 1922.

JOHN J. CULLINAN.
